[57]

ABSTRACT

A match book assembly having a cover forming packets of match sticks, each of which is provided with a separate igniting means to insure proper ignition of a match when it is struck by being withdrawn from the packet. The packets are permanently closed to prevent accidental ignition of the unused matches as a match is being lit. The match sticks are formed by cuts through a paper board so that the heads of the match sticks are surrounded by the paper board sheet. Preferably, the match sticks are arranged in a plurality of groups, each group being separated from an adjacent group by a space in the paper board which is relatively wider than the space which separates each of the match sticks within a group. In addition, a side of each of the match sticks is defined in the paper board by misaligned, overlapping cuts through the paper board sheet. The length of the cut defining the head portion of the match stick is preferably less than the length of the cut defining the tail portion of the match stick, so that the strip between the cuts is disposed nearer to the head of the match stick than to the end opposite the head.

PAPER MATCH BOOK ASSEMBLY

BACKGROUND OF THE INVENTION

This invention relates to match books. More particularly, this invention relates to an improved match book wherein each match is lit on a separate igniter strip as it is withdrawn from the match book. Still more particularly, this invention relates to a paper match book assembly which includes match sticks defined by cuts in a paper board sheet wherein the match sticks are preferably arranged in a plurality of spaced groups, and wherein a cut defining the head portion of the match stick is shorter than a cut defining the tail portion of the stick, so that an intermediate strip between the cuts is located nearer to the head of the match.

In conventional book type paper matches, a plurality of rows of match sticks are stapled together at their lower ends within a cardboard folder. The end of the folder to which the matches are stapled includes an igniter strip formed of an abrasive chemical upon which a match is struck for lighting. The other end of the folder is folded around the matches and fits under the abrasive strip to form a removable cover.

With this type of match book, a match stick is torn from one of the rows of matches and the tip of the match is struck on the abrasive strip to light the match. As a safety measure, it is necessary that the cover be closed before the match is struck.

One disadvantage of this type of match book is that the abrasive strip must be used repetitively until the entire book is used. As the surface of the strip is worn away, it becomes increasingly difficult to light one of the matches and often the match must be struck several times before it is lit, if at all.

A significant disadvantage to the general type of match book described above is the possibility that it may constitute a safety hazard when the cover is not closed before the match is struck, since resulting sparks may ignite the remainder of the matches within the book and perhaps burn the hand of the holder.

An improved paper match book assembly which overcomes these problems is described in U.S. Pat. application Ser. No. 751,302, filed May 17, 1968, now U.S. Pat. No. 3,536,188, issued Oct. 27, 1970 to the same inventors. This invention is a further improvement over the invention there described and includes a number of distinguishing and significant features, as will be apparent from this specification.

Accordingly, it is an overall object of this invention to provide an improved paper match book assembly.

It is another object of this invention to provide an improved match book assembly in which a paper board sheet defines a plurality of match sticks formed therein by cuts through the sheet.

It is an additional object of this invention to provide a paper match book assembly which includes a paper board sheet defining a plurality of match sticks wherein the sticks are grouped so that a space between the groups of matches is greater than the space between adjacent matches within a group.

It is an additional object of this invention to provide a paper match book assembly wherein matches are defined by cuts in a paper board sheet so that the length of the cut defining the head of the match is less than the length of the cut defining the tail portion of the match so that the strip between the cuts is located nearer to the head of the match than to the end opposite the head.

These and other objects of this invention will become apparent from the review of the accompanying written description of the invention, taken in conjunction with the accompanying drawings.

BRIEF SUMMARY OF THE INVENTION

Directed to overcoming the deficiencies of the prior art, and achieving the aims and the objects stated above, this invention relates to an improved paper match book assembly of the type which comprises a paper board sheet having a plurality of match sticks formed therein by cuts through the paper board

sheets. The match sticks formed in the paper board sheet are grouped into a plurality of groups so that the space between adjacent groups of match sticks is greater than the space between adjacent matches within a group. This feature has the substantial advantage of providing a structural rigidity to the match book assembly to provide a reliable and efficient operation in striking each and every match in the assembly.

One side of the match stick is defined by the length of the cut in the paper board sheet while the other side of each of the match sticks is defined in the sheet by misaligned, overlapping cuts through the paper board sheet which respectively define the head portion and the tail portion of the match stick. The length of the cut defining the head portion of the sheet is preferably less than the length of the cut defining the tail portion so that the intermediate strip between the cuts lies nearer to the head of the match stick than to the tail.

The match book assembly according to the invention provides an unused portion of an igniter strip for each match to insure lighting of the match as it is withdrawn from the match book. The invention also contemplates maintaining the match tips completely enclosed within the match book cover until each match is used. Thus, exposure of the matches to sparks which might cause accidental lighting is eliminated, and damage to the ignition portion of the match due to moisture is reduced. Thus, the match book assembly of the invention provides an improved igniting means which insures ignition of a match upon the igniter strip and also a separate igniting means for each match stick.

BRIEF DESCRIPTION OF THE DRAWINGS

FIG. 1 is a view in perspective of the preferred embodiment of the paper match book assembly according to the invention; and

FIG. 2 is a plan view of the paper board sheet of FIG. 1, illustrating the grouping of the match sticks in the assembly and the arrangements of the cuts which define each match.

DESCRIPTION OF THE PREFERRED EMBODIMENT

As may be seen in FIG. 1, the improved paper match book assembly according to the invention is designated generally by the reference numeral 10. The assembly 10 is manufactured from a cardboard strip 12 having the ends 14 folded over to form two packets 16 of matches. The sheet 12 is bent at about the portion 18 which acts as a hinge so that the packets 16 will overlie each other in the general shape of a booklet.

Each packet 16 includes a plurality of match sticks 20 which are defined by cuts or slits in a paper board sheet 22. The surrounding portion 23 of the sheet 22 and its extension portion defined by the wider spacers designated by the reference numeral 24 are secured to the strip 12 by any suitable means, such as by an adhesive.

A plurality of spacers, designated generally by the reference numerals 24 and 25, are provided between the match sticks 20 by the portions of the paper board left between the match sticks 20 after they are cut. The spacers 24 are relatively wider than the spacers 25 for reasons which will be discussed hereafter.

The entire profile of each of the match sticks 20 is cut entirely through the board 22, except for the small connector 26 located between the head portion 28 and the tail portion 30 of each of the match sticks, and nearer to the head portion 28 thereof. The connectors 26 operate to secure each of the match sticks to the paper board to retain the sticks in place in the assembly. The connectors 26 are formed by two misaligned cuts in the match stick profile as shown in FIG. 2. The portion of the board 22 surrounding the tail portion 30 of the match sticks 20 is cut away so that the tail portions 30 extend beyond the edge of the surrounding portion 23 of the sheet 22 and out of the packet 16. Thus, a user can grasp the tail end 30 of the match stick for purposes of withdrawing it from the packet 16.

The matchbook assembly disclosed in FIGS. 1 and 2 of this invention differs from the match book assembly of the applicants shown in application Ser. No. 751,302, referred to above, in at least two major respects. First, the cutting of the match sticks 20 formed in the paper board 22 is different from that of the earlier application in that the spaces between the matches are both wide and narrow. Thus, a plurality of match sticks 20 define a group of match sticks and the separation between adjacent groups of sticks is generally greater than the separations between the match sticks in any one group. 10 Secondly, the location of the connector is located nearer the upper portion of each of the match sticks.

Thus, each packet 16 contains a plurality of match sticks 20 which are divided at least into two groups by the relatively wide spacers 24 extending from the upper portion of the surrounding portion 23 of the paper board 22 and to assure that the match sticks will be more easily ignited when withdrawn from the packet. In addition, the structural integrity of the overall assembly is significantly improved.

As is specifically shown in FIG. 2, the match sticks 20 are divided into three groups designated generally by the reference numerals 32, 33, and 34 respectively. The left-hand portion of each of the match sticks in group 32 is defined by a pair of misaligned cuts on the left-hand portion of each of the sticks, while in group 34, the right-hand edge of each of the match sticks is defined by the misaligned cuts. In group 33, located between groups 32 and 34, one-half of the two misaligned cuts are located on the left-side of the matches, while the other half of the matches have their right-hand portions defined by the misaligned cuts. In this manner, the narrow spacers 25 are located between each match stick 20; the wider spacers 24 are located between the groups of match sticks; and the small connectors 26 are arranged so that the ends of each match stick extend beyond the edge of the remainder of the paper board sheet 22 and out of the packet 16. Moreover, the match stick has its maximum width near the tail portion 30 thereof, so that the tail portion 30 of each match stick are positioned substantially on a side by side basis. When the paper board is fastened to the folder by an adhesive material, the small connectors defined in the paper board by the misaligned, parallel, overlapping cuts are covered by an end 14 of the strip 12 so that the appearance of the packet is attractive and aesthetically pleasing.

The inner portion of the folded-over edge 14 of the strip 12 forming each packet 16 is provided with an igniter band 40 made from an abrasive chemical material suitable for igniting the phosphor heads 42 which form the ends of the match sticks 20 when the heads 42 are rubbed across the band 40. A second igniter band 44 of the same material as the first igniter band is also provided mounted on a strip inside the packet 16 opposite the first igniter band, so as to sandwich the match sticks 18 and the board 22 between them.

When withdrawing a match stick from one of the packets by grasping its exposed edge and pulling outwardly, the connector 26 is torn to release the match from the packet and to permit the match head 42 to rub over both igniter bands 40 and 44, causing simultaneous abrasion of both sides of the match head, thus reliably insuring ignition of the match. Since each of the match sticks are spaced from one another, only one portion of each of the igniter bands is available to ignite an individual match head. Consequently, each match stick is provided with an unused section of the igniter bands to facilitate ignition of the match.

Because each packet is an integral packet which is never opened, the unused match head 42 is covered during the time the match stick 20 is struck, and there is no chance of the remainder of the match sticks being accidentally ignited. Thus a significant advantage of the invention is to provide for improved safety.

It will be appreciated that the above description of the embodiments are illustrative only and numerous modifications and variations may be made in light of the above teachings. It is therefore to be understood that within the scope of the ap-

5 pended claims, the invention may be practiced otherwise than is specifically described herein.

What is claimed is:

1. A paper match book assembly comprising:
a paper board sheet having a plurality of match sticks formed therein by cuts through said paper board sheet wherein portions of said paper board sheet separate the head of said match sticks and a portion of the stick portion of said match sticks, a plurality of said match sticks defining a group of said match sticks and wherein said assembly defines at least a pair of said groups, the spacing between the head portions of adjacent matches in any one group being less than the spacing between adjacent groups, a portion of said paper board sheet being cut away leaving the end of said stick portion opposite said head portion apart from said paper board sheet and extending therefrom, one side of the stick portion of each of said sticks being defined in said paper board by misaligned, overlapping cuts through said paper board sheet thereby to provide a thin strip of paper board interconnecting said match sticks with the remainder of said paper board sheet;

20 a cover forming an enclosure enclosing at least a portion of said paper board sheet containing said heads of said match sticks, and

25 an igniter band mounted on said cover in a manner so that as each of said match sticks is withdrawn from said cover by pulling a match stick by the end opposite the head of such match stick the head of such match stick rubs against said igniter band, each match stick rubbing against a different portion of said igniter band upon being withdrawn from said cover, said igniter band being of a material to ignite said match heads when rubbed thereby.

30 2. The paper match book assembly as set forth in claim 1 wherein each of said matches is defined by a plurality of cuts in said paper board sheet, one side of each of said matches being defined by a cut having a first length and the other side of said match being defined by a first slit and a second slit, said first slit being misaligned with respect to said second slit to define said thin strip, said thin strip being disposed nearer to the head of said match stick than to the end of the said match stick opposite said head.

35 3. The paper match book assembly as set forth in claim 2 wherein the left edge of each of the match sticks in one group is defined by a cut of said first length and the right edge of each of the match sticks in another group is defined by a cut of said first length.

40 4. The paper match book assembly as set forth in claim 3 further including an intermediate group of match sticks located between said one group and said another group and spaced therefrom, each of the left edges of some of the match sticks in said intermediate group being defined by a cut of said first length, and each of the right edges of the remainder of the match sticks in said intermediate group being defined by a cut of said first length.

45 5. A paper match book assembly comprising:
a paper board sheet having a plurality of match sticks formed therein by cuts through said paper board sheet wherein portions of said paper board sheet separate the head of said match sticks and a portion of the stick portion of said match sticks, a portion of said paper board sheet being cut away leaving the end of said stick portion opposite said head portion apart from said paper board sheet and extending therefrom, one side of the stick portion of each of said sticks being defined in said paper board by misaligned, overlapping cuts through said paper board sheet thereby to provide a thin strip of paper board interconnecting said match sticks with the remainder of said paper board sheet, said thin strip being disposed nearer to the head of said match stick than to the end of the said match stick opposite said head,

50 a cover forming an enclosure enclosing at least a portion of said paper board sheet containing said heads of said match sticks, and

an igniter band mounted on said cover in a manner so that as each of said match sticks is withdrawn from said cover by pulling a match stick by the end opposite the head of such match stick the head of such match stick rubs against said igniter band, each match stick rubbing against a different portion of said igniter band upon being withdrawn from said cover, said igniter band being of a material to ignite said match heads when rubbed thereby.

6. The paper match book assembly as set forth in claim 1 further including means for mounting said paper board sheet within said enclosure said mounting means including an adhesive applied to one surface of the portion of said sheet which surrounds the heads of said match sticks and to one surface of an extension portion of said sheet which defines the wider spacing between adjacent groups of sticks.
